UNITED STATES PATENT OFFICE.

GEORGE B. KELLY, OF BOSTON, MASSACHUSETTS.

KEY-HOLDING DEVICE FOR ORGANS.

SPECIFICATION forming part of Letters Patent No. 361,949, dated April 26, 1887.

Application filed June 29, 1885. Serial No. 170,093. (No model.)

To all whom it may concern.

Be it known that I, GEORGE B. KELLY, a citizen of the United States, residing at Boston, in the county of Suffolk and State of Massachusetts, have invented certain new and useful Improvements in Organs; and I do hereby declare that the same are fully described in the following specification, and illustrated in the accompanying drawings.

10 The object of this invention is to provide for organs a device for prolonging the sound of a given note after the player's finger is removed from the key, and to furnish a convenient attachment by which said device may be thrown 15 into and out of action while the player's hands are otherwise occupied.

My invention consists in a series of depending hooks fixed rigidly beneath the several keys, in combination with a pivoted and spring- 20 pressed bar or frame adapted to engage automatically and successively with said hooks.

It also consists in the various devices and combinations of devices set forth in the appended claims.

25 In the drawings, Figure 1 is a transverse section of the key-board, showing one of the hooks engaged with the bar to hold the corresponding key down. Fig. 2 is a front view of a portion of the instrument. Fig. 3 is a detail in 30 perspective.

A represents the keys, and B the hooks secured thereto and extending downwardly therefrom.

C is a movable bar or frame, preferably 35 pivoted in a bracket, D, at each end of the key-board, as shown at E, so that its beveled lip or edge c may in one position engage with any one of the hooks B, and in its other position will not so engage. The object of this engagement 40 of one key at a time is to cause the note corresponding thereto to be sounded during such period of time as the organist desires; and it is obvious that the movement of the bar C, or of an equivalent device, may be effected in various ways, such as sliding in grooves or ways 45 with a spring to give a yielding action.

I furnish the frame or bar C with a light spring, G, which will permit said bar to yield on its pivot when, by pressure of the player's 50 finger on one of the keys, the beveled face of one of the hooks B is forced down past the lip c of

the bar, said spring then causing such lip to engage with the hook, and thus to hold the key down until another key of the same bank is struck, releasing the first hook and engaging 55 another.

The drawings represent a wire torsion-spring, having one end inserted in the pivoted bar C, and the other in its bracket so as to have the proper tension. The bar has an arm, H, 60 provided with an adjusting-screw, J, with a terminal pad, I, by which devices the movement of the bar C on its pivot may be checked at the proper point.

I provide a slide, S, which may be worked to 55 right or left by the player's knees, and for this purpose I furnish a knee-piece, K, attached to the slide and projecting downward midway between the pivoted pedals P. This slide has an upright arm, M, controlling in any convenient 70 way the frame or bar C, so that in one position the lip c is held out of contact with the hooks B, and in the other it may engage with them. The arrangement shown in the drawings I find to work satisfactorily. A spring, N, of greater 75 power than the spring G, is secured beneath the cross-piece O, and bears down upon a part, C', of the pivoted frame or bar C to throw the lip c out of range of the hooks B. There is a stud-roller, Q, at the upper end of the arm M of the 80 slide, which stud extends under the spring N, and gradually lifts its free end off from the frame C, when the slide is moved to the left, so as to leave the frame free to rise under the action of the light spring G, and to be moved by 85 contact of the bevel-hooks with the lip c, as already stated. When the slide is moved again to the right, the spring N is released and again tilts the frame C out of reach of the hooks. The hooks are arranged in a straight line, and 90 are preferably secured each to its key by a screw, b, passed through a slot formed parallel to the key in the body of the hook, so that the hooks may be adjusted toward and from the frame or bar C. The heads of the screws b are 95 shown in Fig. 1. They secure the hooks rigidly to the keys when properly adjusted.

In order that the knee-piece K may not be in the way when it is not desired to use the slide and connected parts, I joint said piece centrally, 100 as at V, so that it may be turned up out of the way, as indicated in dotted lines, Fig. 1, and I

provide a spring-catch, W, which holds the pivoted part of the knee-piece in each of its two positions.

I claim as my invention—

- 5 1. In an organ, the keys A, each provided with a depending hook, B, fixed rigidly beneath it, in combination with a spring-actuated pivoted bar or frame, C, adapted to engage successively and automatically with said hooks B, substantially as and for the purpose set forth.
- 10 2. In an organ, the keys A, and adjustable slotted hooks B, in combination with a movable bar or frame and with a spring permitting said bar or frame to yield to pressure applied to the keys, substantially as set forth.
- 15 3. The combination of keys A, hooks B, and movable bar or frame C, with a spring, G, and an adjusting-screw, J, substantially as set forth.
- 20 4. The combination of keys A, hooks B, and

spring-pressed bar or frame C, with a slide adapted to move said bar or frame into or out of engagement with said hooks, and provided with a folding knee-piece, K, substantially as set forth.

5. The combination of keys A, hooks B, and movable bar or frame C, with a slide adapted to engage or disengage said parts, and with a folding knee-piece located midway between the pedals P, to come between and be operated by the knees of the player, or to turn up out of the way, substantially as and for the purpose set forth.

In testimony whereof I hereto affix my signature in presence of two witnesses.

GEO. B. KELLY.
